PICKER-MOTION FOR LOOMS.

SPECIFICATION forming part of Letters Patent No. 739,526, dated September 22, 1903.

Application filed June 15, 1903. Serial No. 161,407. (No model.)

To all whom it may concern:

Be it known that I, ALFRED H. WHATLEY, a citizen of the United States, residing at Providence, in the county of Providence and 5 State of Rhode Island, have invented a new and useful Improvement in Picker-Motions for Looms, of which the following is a specification.

This invention has reference to an improvement in looms, and more particularly to an improvement in picker-motions for looms.

In looms as heretofore constructed the picker-sticks are usually pivotally secured on the outer ends of the rocking rail of the lay 15 and extend upward through the shuttle-boxes. The pickers are secured to the picker-sticks, and when the picker-sticks are thrown by the mechanism of the loom in the usual way the pickers move on a line forming a segment 20 of an arc the center of which is the pivot of the picker-sticks. This motion of the picker-sticks gives an upward and downward movement to the picker in the shuttle-boxes and an irregular movement to the shuttle, causing the shuttle to jump and smash 25 the warp-threads in the loom.

The object of my invention is to prevent bad weaving or smashing of the warp-threads by an irregular movement or throw of the 30 shuttle, and I accomplish this object by mechanism controlling the picker-stick, giving to the picker-stick a movement corresponding to the true movement required of the shuttle—that is to say, the picker on the picker-stick now moves on a straight line drawn lengthwise through the center of the shuttle-boxes and the shuttle.

My invention consists in the peculiar and novel construction of a mechanism adapted 40 to control the movement of a picker-stick to move the picker on the picker-stick in a straight line in the shuttle-box, as will be more fully set forth hereinafter.

Figure 1 is a front view of a loom with my 45 improved picker-motions, showing the picker-sticks in their normal positions in full lines and in their inward and outward positions in broken lines. Fig. 2 is an enlarged front view of the picker-motion mechanism detached 50 from the loom, showing the frame supporting

the cam and link for controlling the movement of the picker-stick and the springs holding the picker-stick in its normal position; and Fig. 3 is a sectional view taken lengthwise through the picker-stick and picker-motion mechanism. 55

In the drawings, *a* represents the rocking rail, *a'* the picker-sticks, and *a²* *a²* the shuttle-boxes, of a loom. The rocking rail extends through bearings in the loom sides and 60 supports the lay of the loom in the usual way, and the picker-sticks are operated by the picking-cones and picker-straps of the loom to throw a shuttle from the shuttle-boxes.

My improved picker-motion mechanism is 65 secured on the ends of the rocking rail *a* by the frames *b* and control the movement of the picker-sticks *a'*. The frame *b* consists of the cylindrical body *b'*, secured to the end of the rocking rail *a*, with the upper arm *b²* 70 curved upwardly and outwardly and having the enlarged end *b³* with the slot *b⁴* and the lower outwardly-extending arm *b⁵*, forming a support for the link *c*, pivotally secured to it by the bolt *c'*. The picker-stick arm *d* has 75 the elongated open recess *d'*, shaped to receive the lower end of the picker-stick. It is pivotally secured in the link *c* at its lower end by the bolt *c²* and held in its normal position by the flat springs *c³* and *c⁴*, secured at 80 their lower ends to the link *c* by the bolts *c⁵*, as shown in Fig. 2. The adjustable cam-plate *e* with the cam-slot *e'* is secured to the arm *b²* by the bolt *e²*, forming a pivot, and the bolt *e³* through the slot *b⁴* in the end of the 85 arm *b²*. The lower end of the picker-stick is secured in the recess *d'* in the arm *d* by the bolt *d²* and the bolt *f*, having the head *f'* between the cam-plate *e* and the arm *b²* and carrying the roll *f²*, working in the cam-slot 90 *e'* in the cam-plate *e*. As the position of the picker-sticks varies in different looms, the cam-plate *e* is made adjustable by moving the outer end of the cam-plate upward or downward and securing it in the position required by the tightening of the nut on the bolt *e³*. 95

In the operation of my improved picker-motion the shuttle is thrown from the shuttle-box by the picker-stick against the ten- 100

sion of the spring c^3 , which takes the place of the usual floor-spring. The roll f^2 follows in the cam-slot e' and raises the picker-stick and link c , as shown in broken lines on the right of Fig. 1. The tension of the spring c^3 now returns the picker-stick to its normal or central position. The return blow of the shuttle carries the picker-stick outward against the tension of the spring c^4 , acting as a check to neutralize the blow of the shuttle. The roll f^2 in the cam-slot raises the picker-stick and the link c , as shown in broken lines on the left of Fig. 1. The link-pivot, the pivot of the picker-stick arm, and the cam-plate with the cam-slot e' are so placed and adjusted as to give to the picker on the picker-stick a straight-line movement in the shuttle-box.

By the novel construction of the mechanism of the picker-motion the blow is given in a straight line on the shuttle by the picker on the picker-stick, the liability of smashing the warp-threads is eliminated, and a more perfect weave is attained than has heretofore been done.

Having thus described my invention, I claim as new and desire to secure by Letters Patent—

1. In a picker-motion for looms, mechanism controlling the picker-stick, consisting of a frame, a link pivotally secured to the frame, an arm pivotally secured to the link and supporting the picker-stick, a plate having a cam-slot adjustably secured to the frame, and a roll on the arm supporting the picker-stick working in the cam-slot in the plate, for the purpose as described.

2. In a picker-motion, mechanism controlling a picker-stick, consisting of a frame secured on the end of the rocking rail of a loom, a link pivotally secured to the frame, an arm pivotally secured to the link, a picker-stick secured in the arm, a plate having a cam-slot adjustably secured to the frame, and a roll

on the arm supporting the picker-stick working in the cam-slot in the plate, for the purpose as described.

3. In a picker-motion, mechanism controlling a picker-stick, consisting of a frame secured on the end of the rocking rail of a loom, a link pivotally secured to the frame, an arm pivotally secured to the link, a picker-stick secured in the arm, a spring secured to the link and acting on the arm to return the picker-stick to its normal position, a spring secured to the link and acting on the arm as a check to neutralize the blow of the shuttle on the picker-stick, a plate adjustably secured to the frame, a cam-slot in the plate, and a roll on the arm supporting the picker-stick working in the cam-slot in the plate, as described.

4. In a picker-motion for looms, the combination with the frame b , consisting of the cylindrical body b' having the arm b^3 with the enlarged end b^3 in which is the slot b^4 , and the arm b^5 , of the link c pivotally secured to the arm b^5 by the bolt c' , the picker-stick arm d having the recess d' and pivotally secured to the link c by the bolt c^2 , the flat springs c^3 and c^4 secured to the link c by the bolts c^5 c^6 , the adjustable cam-plate e with the cam-slot e' secured to the arm b^3 by the bolt e^3 forming a pivot, and the bolt e^3 through the slot b^4 , the picker-stick a' secured in the recess d' in the arm d by the bolt d^2 and the bolt f , having the head f' and carrying the roll f^2 working in the cam-slot e' , and means for securing the frame b to the end of the rocking rail of a loom, as described.

In testimony whereof I have signed my name to this specification in the presence of two subscribing witnesses.

ALFRED H. WHATLEY.
